(57) **CLAIM**

We claim the ornamental design for an appliance display
screen or portion thereof with graphic user interface, as
shown and described.

DESCRIPTION

FIG. 1 is a front view of a first image in a sequence of an
appliance display screen or portion thereof with graphic user
interface according to the design;

FIG. 2 is a front view of a second image in the sequence
thereof; and,

FIG. 3 is a front view of a third image in the sequence
thereof.

The broken lines depict portions of the article that form no
part of the claimed design.

Dash-dot broken lines represent the appliance display screen
as well as the bounds of the claimed design and form no part
of the claimed design.

(Continued)

The appearance of the graphic user interface sequentially transitions between the images shown. The process or period in which one image transitions to another forms no part of the claimed design.
